UNITED STATES PATENT OFFICE.

GEORGE D. BURTON, OF BOSTON, MASSACHUSETTS, ASSIGNOR TO THE BURTON COMPANY, OF BOSTON, MASSACHUSETTS, A CORPORATION OF MASSACHUSETTS.

METHOD OF TREATING POROUS AND FIBROUS MATERIAL.

1,123,166.

Specification of Letters Patent.

Patented Dec. 29, 1914.

Application filed September 24, 1912. Serial No. 722,047.

To all whom it may concern:

Be it known that I, GEORGE D. BURTON, a citizen of the United States, and resident of Boston, in the county of Suffolk and State 5 of Massachusetts, have invented certain new and useful Improvements in Methods of Treating Porous and Fibrous Material, of which the following is a specification.

This invention relates to a method for 10 converting fibrous vegetable material into pulp, and is particularly adapted for pulping corn stalks, rice and flax straw, grasses, and the like, although it is not restricted to such use, but may be employed for digesting 15 any sort of pulp material.

An apparatus suitable for carrying out the method is shown in the accompanying drawings and described in detail in the following specification, although I declare 20 that I do not restrict my invention to the exact form and construction there shown and described, but include within the scope thereof any forms of apparatus capable of obtaining substantially the same results in 25 substantially the same or an equivalent manner.

In the accompanying drawings, Figure 1 is a plan view of the apparatus embodying 30 the features of the present invention. Fig. 2 is a longitudinal sectional view of the same. Fig. 3 is a cross section of the same. Fig. 4 is an elevation of the right hand end. Fig. 5 is a sectional view showing a detail of construction of the apparatus. Fig. 6 is a detail elevation and Fig. 7 a perspective view 35 of an electrode employed as a part of the apparatus in carrying out the process effected by the apparatus.

The same reference characters indicate the 40 same parts in all the figures.

I will first describe the apparatus illustrated, and then explain the steps of the method in which the invention particularly resides, and in the carrying out of which 45 this apparatus is used.

The apparatus includes in its construction a stationary outer shell 1 and a revoluble inner shell 2, the former being water tight except for the openings hereinafter 50 described and the latter being perforated in its cylindrical walls and having perforated transverse partitions 3, as shown in Fig. 2. The outer shell is secured in a stationary condition upon supports 4, 4 and has in its 55 upper side a number of manholes 5, one

being over each of the compartments of the inner shell, such manholes being tightly closed by removal covers 6. In the ends of the outer shell are packed bearings 7 which contain rotatably the trunnions 8 which project from the heads of the inner shell, and through these trunnions there passes a shaft 9 to which the inner shell is secured. Said shaft is additionally supported by bearings 10, 11 and carries gear wheels 13, 14 which mesh with pinion gears 15, 16 on a driving shaft 17. The latter carries also a gear 18 in mesh with a pinion 19 on a counter-shaft 20 upon which latter are also secured tight pulleys 21 22 and a loose pulley 23 adapted to be engaged alternately by belts 24, 25 passing over pulleys on a shaft 26. These belts drive in opposite directions and are shifted from time to time by a shipper mechanism 27. Thereby the inner shell 75 is rotated for a number of turns, first in one direction and then in the other. A pipe 28 is connected at a number of points with the outer shell and serves to admit steam or a pulping solution to be used in carrying out 80 the pulping process. Another pipe 29 is also connected with the outer shell at the bottom thereof for drawing off the solutions therefrom. A pipe 30 is connected with the shell preferably at the top thereof for admitting water and solutions thereto. All of these pipes are provided with valves by which communication through them may be made and interrupted. There are also pipes 31 and 32 leading from the upper part of 85 the outer shell to a trap 33, which latter communicates with a condenser, consisting conventionally of a pipe coil 34 in a tank 35 through which cooling liquid may flow. These pipes are also provided with valves 90 whereby either or both may be opened or closed.

I provide means for directing an electric current through the solution in the digester at such times as the digesting process requires. Such means comprises electrodes 36 and 37, indicated in dotted lines in Fig. 2, which are mounted at widely separated points in the outer shell and are connected with conductors 38 and 39, which carry an 105 electric current from a source of supply through a switch 40. One of the electrodes, which is typical of both, is shown in detail in Figs 6 and 7. Said electrode is an aluminum bar 41 of suitable dimensions and 110

mass for the current handled, which is supported at or near its ends in chairs 42 of any suitable insulating material, such as porcelain, which chairs are secured to the outer shell. The conductors to the electrodes pass through insulating plugs and are attached to the bars by binding nuts 43. The insulating plugs may be located at any desired points in the shell near the electrodes, whether in the ends or sides of the shell being immaterial, as the shell is stationary. A preferred form of insulating plug is shown in Fig. 5 and consists of a threaded tube 44 screwed into the shell 1, having a bore considerably larger than the conductor, which conductor is held centrally by a mass of insulating material 45.

Having described the construction of my pulp digester in detail, I will now describe my improved method of producing pulp from cornstalks, straw, grass, etc.

The ingredients of the pulp, whether the same is corn-stalk, rice or flax straw, cotton stalk, or any other porous and fibrous materials, mixed or separate, are put in the inner cylinder with a saponaceous solution of a strength approximately from 3 to 5 per cent., more or less, or equivalent washing liquor, for the purpose of washing out dust, earth, the black or creosote joint in the corn stalk, also the seeds or grains and tassel of the corn, rice, flax, etc., and any other deleterious substances which may be mingled with the stalks or straw. The driving machinery is set in operation and the inner drum is thereby revolved first in one direction and then in the other, lifting and dropping the mass of pulp material and subjecting it to thorough washing. The perforations in the inner drum are sufficiently large to allow the dirt, seeds, and kernels of grain to pass through, whereby they may be drawn off through the outlet pipe 29 with the washing solution. In the pulping of the materials named the removal of dirt, seeds, etc., is essential to the production of clean pulp, and this character of digester accomplishes such removal completely and perfectly. More particularly in the treatment of flax straw, the removal of the flax seeds is essential. After their removal, as described, these seeds are drawn off, washed and dried, and become a useful and valuable by-product. The same is also true in regard to rice grain in the treatment of rice straw. Sometimes there is a considerable quantity of flax seed or rice kernels in the straw, coming from heads which were green when the straw was threshed but subsequently ripened as the straw was dried. All the seeds or kernels remaining in the straw after drying preliminary to the pulping operation become dislodged readily during the agitation and pass through the perforations and are withdrawn. This same method is effec-

tive in the treatment of cotton stalks, as there is sometimes more or less cotton seed on such stalks, and also in the treatment of any other kind of porous or fibrous material for cleaning the same, since thereby I am able to remove all seeds and gummy substances contained with the stalks or straw, as well as dirt and coloring matter in the same. After the washing is completed and the washing solution is drawn off, any proper dissolving or digesting solution is admitted to the digester without necessitating removal of the stalks. The same agitation is effected by the revolution of the inner drum back and forth when at the same time, if required, steam may be introduced through the pipe 28. Any suitable digesting solution which is best adapted to the substance under treatment may be employed in this operation. The electrodes and the electric circuit described are used in this process, when desired, for purposes either of heating or of electrolysis of the solution or both. The solution between the electrodes completes the circuit, and this solution is both heated by the current and somewhat decomposed. The elements produced by electrolysis air in digesting and in bleaching the pulp, the latter effect being accomplished by the nascent oxygen so produced. When the pulping operation is complete, the mass is sufficiently fluid to flow through the perforations in the inner drum and to be drawn off from the outlet pipe 29.

Sometimes weeds are cut with the stalks and dried with them. Such weeds are automatically separated from the pulp when the digestion of the latter is complete, because they do not dissolve when subjected to the pulping solution required for stalks and straw, and therefore when the pulp passes from the digester, the weeds remain inside the inner cylinder and may be removed when desired. It is of great advantage in the production of good clean pulp from stalks, straws, etc., that weeds be entirely eliminated. This apparatus enables complete separation of the weeds to be effected, and is the only one of which I have knowledge capable of securing this result.

The machine may be made of any material, either entirely of metal or partly of metal and partly of wood, or of any other material. Where the machine is entirely of metal, I avoid danger of short circuit of the electric current through the machine itself, by the insulating material previously described, and also by a division and insulation of the driving shaft 17, such driving shaft being made in two parts connected by a coupling 46, shown in Fig. 1, which is wholly or partly of non-conducting material.

The mechanism for revolving the inner

shell is so designed that it causes the same to rotate preferably several turns in one direction and then a like number of turns in the other direction. The reversals are particularly important for the carrying out of my process, as they cause the pulping mass, which has been carried to the top of the inner drum by the rotation thereof and by centrifugal force, to fall when the drum reverses, and then to be picked up in the opposite direction. This drop of the pulp and its carriage in opposite directions tends to beat up the substance and force out the dirt particles, seeds, etc., and in the digesting process to quickly and thoroughly mingle the solution with the pulp. Thus in both steps of the process, the desired results are effected more rapidly than is possible with other machines.

20 I have found that by means of this apparatus and the process with which it is used, I can take a mixture from one-half to two-thirds corn stalks and one-third to one-half waste flax straw, or other stalks, grasses, or straws, and produce a high quality of pulp of good length and strength, which can be manufactured into leather board, card board, or paper, and molded or pressed into any desired shape. The pith of the corn stalk makes a good filler for the pulp when mixed with the fibrous materials mentioned, or others. The apparatus also enables the alcohol distilled from the vegetable matter by the pulping process to be collected and saved. The alcohol and other vapors in the upper part of the shells are allowed to pass through the pipes 31 and 32 to the condenser, from which they are drawn in liquid condition for further treatment.

40 From the foregoing description it will be seen that I have provided an efficient apparatus for separating dirt, seeds, etc., from corn and other stalks and straws, for converting such stalks and straws rapidly into pulp and bleaching the pulp, for separating weeds from the pulp, and for reclaiming alcohol. The stalks or straw may be put into the inner shell or container whole, that is, without being cut into short lengths, and just as they come from the field after being dried, that is, with the weeds and any other porous substances or material that may be mixed with them. The washing and digesting steps of the process carried out while the material remains in the inner perforated container, as above described, enable all these foreign things or substances to be completely and effectively separated from the pulp which is finally obtained from the material. The pulp secured as the finished product has a long fiber and is homogeneous in character, being thereby very tough and strong, and having the qualities necessary to produce high grade paper.

65 My process saves more than half the time

now required by other methods, and saves labor and produces a better, cleaner, and stronger pulp.

The washing solution which I consider best adapted for the purpose of removing dirt and other foreign substances contains borax, sal soda, liquid ammonia, and soap chips, all dissolved and mixed together. The salts mentioned serve to dissolve the silica which forms the protective covering of corn stalks and straw, removing the silicious covering, which, if left in the pulp, would cause the paper made therefrom to be stiff and brittle. The dissolving or digesting solution used in the latter step is preferably a solution containing sufficient caustic soda to bring its specific gravity from approximately 1.010 to 1.015 more or less.

I wish to be understood in the operation of this invention that I may do so with or without the use of a current of electricity, but when a current of electricity is used I usually employ a current which may be obtained from any suitable source and may vary in volume and pressure from 75 to 500 volts and from 6 to 200 amperes, more or less, according to the size of the apparatus and the quantity of the material it is desired to treat at one operation.

95 I claim:

1. The method of converting fibrous material into pulp which consists in placing the material in a perforated container, revolving said container in a saponaceous solution until foreign matter has been removed from the material and carried through the perforations of the container, and then rotating the container in a dissolving solution until the material is sufficiently digested to pass through the perforations of the container.

2. The method of converting fibrous vegetable matter into pulp which consists in placing the vegetable matter in a perforated container, agitating said container in a soap solution until such foreign matter as is attacked by such solution has been removed from the material and has passed out of the container, then agitating the container in a digesting solution containing caustic soda or a substance having an equivalent action, and then separating indigestible weeds from the fibrous pulp material by causing the digested pulp to pass through the perforations of the container.

3. A method of pulping material which consists in placing the material in a perforated container, rotating said container in the solution containing a mixture of dissolved borax, sal soda, soap chips and ammonia to a strength of approximately from three to five per cent., until the dirt, seeds, and other foreign matter commingled with the material have passed through the per-

forations of the container and then similarly rotating the container in a digesting or dissolving solution containing caustic soda in sufficient quantity to bring its 5 specific gravity from approximately 1.010 to 1.015, until the material is sufficiently digested to pass through the perforations of said container.

4. The method of converting corn stalks 10 into pulp which consists in placing the entire corn stalks as they come from the field in a suitable perforated container, revolving said container, in a saponaceous solution until dirt, kernels, the silicious coating of 15 the stalks and other foreign substances have been removed from the stalks and carried through the perforations of the container, then rotating the container in a dissolving solution containing caustic soda or equivalent agent, and then separating weeds from 20 the stalks by causing the digested stalks to pass through the perforations.

5. Method of making pulp from such materials as cornstalks, straws, grasses, etc., 25 which consists in placing said material in a perforated cylinder, revolving said cylinder within another receptacle containing a suitable cleansing solution, for the purpose of eliminating the seeds, dirt, etc., and then 30 removing the waste substance from the outer cylinder, recharging the outer receptacle with a pulping solution, for the purpose of reducing the said materials to a pulpy condition.

35 6. The method of treating porous and fibrous substances for the purpose of removing the deleterious elements contained therein, so that the same may become useful in the arts and trades, which consists in

placing the material to be treated in a perforated revoluble cylinder, revolving said cylinder and its contents in a second tank containing a suitable cleansing solution, then removing the waste matter from the secondary tank and recharging the same 45 with a suitable finishing solution.

7. The method of treating porous and fibrous material for the purpose of eliminating the undesirable substances contained therein, which consists of placing the material to be treated in a perforated cylinder revoluble in a tank or vat containing a cleansing solution, revolving the cylinder a number of turns first in one, and then in the opposite direction, then withdrawing the 50 saturated cleansing solution and adding a different solution and continuing the treating of the material until the same becomes a useful commodity.

8. The method of treating porous and fibrous substances containing seeds, which 55 consists of placing the material in a perforated cylinder revoluble in a tank containing a suitable treating solution for the purpose of washing out the seeds, dirt, etc., 60 and passing the same off through the apertures in the revoluble cylinder by revolving said cylinder in the tank and then subjecting the remaining material in the cylinder to further treatment for the purpose of 65 pulping said material.

In testimony whereof I have affixed my signature, in presence of two witnesses.
